(57) CLAIM

The ornamental design for an armored truck, as shown and described.

DESCRIPTION

FIG. 1 is an upper front left perspective view of the novel armored truck.

FIG. 2 is a left side view of the armored truck of FIG. 1.

FIG. 3 is a right side view of the armored truck of FIG. 1.

FIG. 4 is a top side view of the armored truck of FIG. 1.

FIG. 5 is a front end view of the armored truck of FIG. 1; and,

FIG. 6 is a rear end view of the armored truck of FIG. 1.

The broken lines in FIGS. 1-6 are for illustrative purposes of illustrating portions of the armored truck that form no part of the claimed design.

1 Claim, 6 Drawing Sheets
